LAMP

Carl Moser, New York, N. Y., assignor to Lightolier Co., New York, N. Y., a corporation of New York

Application May 8, 1931. Serial No. 535,877

8 Claims. (Cl. 240—81)

This invention relates to improvements in electric lamps, torches and the like ornamental illuminating devices.

An object is to provide a fixture of the above type, having a plurality of incandescent lamp bulbs, with easily accessible means for separately controlling each of the bulbs.

An additional object is to provide a lighting fixture with which both direct and reflected illumination effects can be produced; and to this end it comprises a reflector of special design and means through which diffused light can be radiated or transmitted in the amount desired.

In its preferred form the invention comprises a floor lamp by which a large portion of the illumination is thrown upward towards the ceiling and another portion is distributed horizontally; with an enveloping shade to moderate the horizontal beams and diminish their intensity if necessary.

It is another object of the invention to provide a lamp of very artistic appearance, but simple in construction, and capable of being easily made and assembled.

Further object is to provide a lighting appliance all of the parts of which contribute to the general decorative effect, while at the same time sustaining all the mechanical relations necessary to constitute a complete structural unit.

The nature and advantages are completely set forth in the description that follows and the novel features are pointed out broadly and specifically in the appended claims. This disclosure, however, is illustrative only and I do not wish to be limited to the construction illustrated herein; but reserve the right to make changes in the shape, size, design and arrangement of the various parts to the full extent consistent with the scope of the invention and the underlying principle thereof.

In the accompanying drawing, in which is shown one of the various possible embodiments of the invention:—

Fig. 1 is a vertical section through a lamp according to this invention.

Figs. 2 and 3 are side views of bracing members used in the construction of said lamp; and

Fig. 4 is a sectional view of a detail.

On the drawing the same numerals identify the same parts throughout.

The numeral 1 indicates a suitable support which may have the form of a tubular standard or column, adjacent the upper end of which is mounted a bowl shaped head 2. Upon this head and affixed thereto is a dish-shaped lamp-carrier 3 to the bottom 4 of which are attached a suitable

number of fixtures in the form of lamp sockets 5 for the incandescent electric lamps 6. The bottom 4 of the carrier 3 is convex, and the sockets 5 are of the well known construction with internal threads to enable the threaded necks of the lamps 6 to be attached by screwing them into these sockets.

The sides 7 of the carrier 3 make a well defined angle with the bottom 4 presenting an outside edge 8 which engages and rests upon an annular shoulder inside of the head 2; this shoulder being indicated at 9 and being surrounded by the upturned rim 10. The bulbs of the lamps 6 may be transparent or translucent and may have any color desired. They are surrounded by a translucent bell or globe 11 which is open at both ends, the lower end being seated upon an annular shoulder 12 in the carrier 3 above the bottom 4 thereof. The bell 11 expands or flares considerably in an upward direction; and at the top it is lined with a metallic reflector element 13, which likewise flares according to the configuration of globe 11. At its upper and larger end the bell is formed to provide an annular bead 14 within which rests the rim 15 of the reflector.

With this construction, part of the light of the lamps passes through the sides of globe 11 and is radiated directly; while another portion of the light from the lamps 6 strikes the reflector 13 and is reflected upward and to some extent outward. Owing to the fact that the bell 11 is flared or expands toward its end remote from the carrier 3, the sockets 5 of the lamp 6 have plenty of room and the axes of the sockets and the lamps can be divergent according to the convexity of the bottom 4.

The sockets 5 can be affixed to the bottom 4 of the carrier 3 in any suitable manner and I have shown diagrammatically fastening means at 16. The sockets will of course incorporate suitable switching means which may be operated by pull chains 17, one depending from each socket said chains passing through the respective openings 17' in the carrier 3. Hence, the supply of electric current to each of the lamps 6 can be controlled and any one or more of the lamps can be illuminated or extinguished independently of the rest.

The top of the column 1 is surmounted by a cap 18 upon which rest bracing members to engage and steady the lamp structure just described. The bracing members in question are illustrated in Figs. 2 and 3, and each comprises a pair of upright arms to the upper ends of which the head 2 is affixed. Though the bracing mem-

bers are two in number, more can be utilized if preferred; and if two are present they are disposed so that the planes of the arms thereof are at right angles. One of the bracing members, 5 for example that shown in Fig. 3, comprises a perforated base 19 from which arise the bracing arms 20 which have concave surfaces 21 at their upper ends to fit against the outside of head 2; and are secured by screws 22. The other brac- 10 ing member, as shown in Fig. 2, comprises a similar perforated disk 23 on the top of which is a boss 24; and from the disk 23 rises as before the bracing arms 25 having upper concave ends 26. When the two bracing members are in po- 15 sition the disk 19 rests upon the cap 18 and disk 23 rests upon the first disk 19. The screws 22 of course have suitable threaded openings in the tops of the bracing arms 20 and 25. The bracing members, and particularly the arms thereof, can 20 have any desired ornamental shape; and the construction just described can easily be made by casting each bracing member, comprising the two arms rigid at their lower ends with a disk, in one piece. When the lamp is made up the head 2 25 and parts associated therewith are thus braced at four equidistant points.

The column 1, as above stated, is hollow and the cap 18 is likewise centrally bored out, one end being threaded if desired to engage the column 30 1 and the other end threaded to receive and hold a tubular extension 27 which passes through the perforations of the disks 19 and 23. This exten- 35 sion also passes through the knob 28, which rests upon the boss 24; and the extension also projects through the bottom of the carrier 2. It is sur- 40 rounded by a spacing sleeve 29 which abuts the knob 28 at one end; and its opposite end engages a similar element 30; the length of this spacing sleeve being such that the element 30 affords a 45 rest for the head 2. Within the head 2, the extension 27 receives a washer 31 and has screw threaded engagement with a hickey 32. The bottom 4 of the carrier 3 is perforated in line with the extension 27, and through this perforation is passed the threaded extension of a hollow nut 33 which screws into the hickey 32.

Thus the parts of the lamp structure are all made rigid with one another and firmly attached to the top of the column 1. The support will of 50 course terminate at its lower end in a suitable pedestal to enable the lamp to stand wherever it is placed. Owing to the fact that the bore through the support 1 is continued through cap 18 to the interior of the carrier 3 the electric 55 conductors can be disposed in the support 1 and passed up through the extension 27 so that they can be connected at their upper ends in the manner required to supply energy to all of the lamps 6.

60 A suitable shade is shown at 34 to surround the globe 11. It has internal fingers 35 to rest upon the upper edge of globe 11 and these fingers may be connected by ring 36.

The illuminating device is thus strongly made, 65 easy to assemble and pleasing to the eye. Part of the light is thrown upward by the reflector 13 and part is radiated, softened and diffused by the globe 11. The light passing through the globe can be further moderated by the shade 34.

70 It will thus be seen that there is herein de- 75 scribed apparatus in which the several features of this invention are embodied, and which apparatus in its action attains the various objects of the invention and is well suited to meet the requirements of practical use.

As many changes could be made in the above construction, and many apparently widely different embodiments of this invention could be made without departing from the scope thereof, it is intended that all matter contained in the above description or shown in the accompanying drawing shall be interpreted as illustrative and not in a limiting sense.

Having thus described my invention, what I claim as new and desire to secure by Letters Patent is:

1. A lighting fixture comprising a tubular support, a perforated cap surmounting the support, a hollow extension rising from the cap, a knob surrounding said extension, a sleeve enveloping the extension and abutting said knob at one end, a head into which the extension projects, a second knob engaging the head and abutting the opposite end of said sleeve, and a hickey in the head attached to the extension to secure the head thereto.

2. The lighting fixture according to claim 1, wherein bracing members are mounted on the first-named cap and affixed to said head.

3. A floor lamp comprising a standard, a head on top of said standard, exposed bracing members extending between the standard and the exterior of the head, a combined shade and lamp holder resting on said head, means securing said holder to said head, including a hickey concealed in said head, and a globe resting in said holder and flaring upward therefrom.

4. A floor lamp comprising a standard, a cupped head at the upper end of said standard, a shade holder unit affixed within said cupped head means securing said holder to said head including a hickey within the latter, a plurality of lamps affixed in said shade holder and a globe having a reduced rim resting in said shade holder, said globe flaring upwardly from said shade holder and encircling said lamps.

5. A floor lamp comprising a standard, a cupped-shaped head affixed to the upper end of said standard, an upwardly convex lamp holder plate resting in said head, means securing said holder plate to said head, including a hickey within the latter, lamps affixed to said plate extending perpendicularly thereto and accordingly diverging, said lamp holder having a rim thereabout and an upwardly flaring globe resting at its lower edge in said rim.

6. In a lighting fixture, the combination of a support and a lamp and shade carrying head, including bracing members exposed between the support and the head, said bracing members comprising a pair of generally similar U-shaped members, each presenting a perforated disk at the base of the U, said disks superposed and affixed to the support and arranged with the legs of the respective U's in planes at right angles to each other, the ends of said legs contacting said head and affixed with respect thereto, the exposed legs of the braces presenting an ornamental conformation disguising the utilitarian function of said members.

7. In a lighting fixture, the combination of a support, a nut affixed to the end thereof, a tube fixed in said nut, a U-shaped bracing member having a perforated base and resting on said nut, a head at the upper end of said tube, a lamp holder supported by said head, and means securing said holder to said head, including a hickey concealed within said head, said bracing member exposed to view and affixed at its upper end to said head.

8. In a floor lamp, the combination of a standard, a nut at the upper end thereof, a tube in said nut, a pair of U-shaped brace members each having a perforated base, said bases superposed and resting on said nut and arranged with the planes of the U's at right angles to each other, a knob about said tube resting on the bases of said braces, a sleeve about said tube and resting on said knob, a second knob about said tube resting on said sleeve and a lamp support head resting on said latter knob, said bracing members secured at their free ends to the exterior of 80 said head.
